CLAIM

The ornamental design for a reservoir, as shown.

DESCRIPTION

FIG. 1 is a front-top perspective view of a first embodiment
of a reservoir showing the claimed design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front-top perspective view of a second embodiment
of a reservoir showing the claimed design;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines shown directly adjacent to the claimed
surface in FIGS. 8-9 illustrate a boundary and forms no part
of the claimed design. The remaining broken lines shown in
FIGS. 8, 9, and 11-14 illustrate portions of the reservoir that
form no part of the claimed design.

The shade lines in the figures show contour and not surface
ornamentation.
